DISPLAY RACK

Lymon Hall, Atlanta, Ga., assignor to H. W. Lay
& Company, Inc., Atlanta, Ga., a corporation
of Tennessee

Application September 18, 1953, Serial No. 26,864

Term of patent 14 years

(Cl. D80—10)

To all whom it may concern:

Be it known that I, Lymon Hall, a citizen of the United States, residing at Atlanta, in the county of Fulton and State of Georgia, have invented a new, original, and ornamental Design for a Display Rack, of which the following is a specification, reference being had to the accompanying drawing, forming a part hereof.

Fig. 1 is a front elevational view of a display rack showing my new design;

Fig. 2 is a side elevational view of the rack;

Fig. 3 is a plan view of the rack, only the uppermost tray being shown for the sake of clarity;

Fig. 4 is a sectional-plan view, on the plane indicated by the line 4—4 in Fig. 1, with the lower two shelves omitted for the sake of clarity;

Fig. 5 is a sectional-plan view, on the plane

indicated by the line 5—5 in Fig. 1, with the bottom shelf omitted for the sake of clarity; and

Fig. 6 is a sectional-plan view, on the plane indicated by the line 6—6 in Fig. 1.

I claim:

The ornamental design for a display rack, as shown.

LYMON HALL.
